UNITED STATES PATENT OFFICE.

JOSEPH PLEENTER, OF FLINT, MICHIGAN.

SCRAPER.

1,411,980.

Specification of Letters Patent. Patented Apr. 4, 1922.

Application filed July 3, 1919, Serial No. 308,433.

Renewed September 16, 1921. Serial No. 501,182.

To all whom it may concern:

Be it known that I, JOSEPH PLEENTER, a citizen of Hungary, residing at Flint, in the county of Genesee and State of Michigan, have invented new and useful Improvements in a Scraper, of which the following is a specification.

This invention relates to traction operated scrapers or scoops, the object being to provide a scoop or scraper which is capable of being lowered for filling and of being raised by power furnished by the traction wheels of the machine.

Another object is the provision of a machine of this character having a vertically movable scoop or scraper guided in the frame and a drum for hoisting the scoop, novel means being provided for locking and releasing the drum to and from its shaft, the latter being driven from the traction wheels of the machine.

Another object is the provision of means included in the drum driving means, which compensates for the turning of the machine, so that one end of the drum carrying shaft will be automatically released when the shaft is making a turn.

Other objects and advantages of the invention will appear as the following description is read in connection with the accompanying drawings.

In the drawings:

Figure 1 is a plan view of a machine embodying the present invention.

Figure 2 is a side elevation with one wheel removed and the cover plate of one of the driving wheels removed to show the ratchet mechanism.

Figure 3 is a longitudinal sectional view.

Figure 4 is a transverse section taken on a line with the hoisting shaft.

Figure 5 is a similar view taken on a line with the axles and looking toward the rear of the machine.

Figure 6 is a detail section showing the ratchet releasing mechanism for dumping the scoop.

Figure 7 is a similar view of the ratchet mechanism for closing the scoop.

Referring to the drawings in detail, wherein like characters of reference denote corresponding parts, the machine embodies a frame 10, which consists of side members and end members and a cross member connected to and located intermediate the ends

of the side members, the said cross member being indicated at 11. Extending from the side member of the frame are stub axles 12, upon which are mounted traction wheels 13, the latter supporting the frame. Connected 60 to the forward end of the frame is a tongue 14. It is, of course, obvious that this tongue may have substituted therefor suitable coupling means for connection with a tractor. Mounted upon the opposite end of the frame 65 is a seat 15, for the convenience of the operator. Mounted for vertical movement in the frame 10, is a scoop 16, the latter comprising side plates 17, an end plate 18 and a bar 19 connecting the forward ends of the 70 side members. This bar is provided with a front cutting edge, which is adapted to dig into the surface of the ground for filling the scoop. The bottom of the scoop is formed by a pair of hinged plates 20, one edge of 75 which is hingedly secured to each of the side plates 17, as shown at 21.

Mounted in bearings 22, carried by each of the side plates 17, is a rotatable shaft 23, this shaft being connected to each of the 80 hinged plates 20 by means of a rope or chain 24. One end of this chain is connected to the bar 19 and passes through guides 25 carried by the plates 20 and has its opposite end connected to and wound upon the shaft 23. 85 The shaft 23 is held against rotation through the medium of a pawl 26, which is pivotally mounted upon one of the side plates 17 and engages a ratchet wheel 27 fast upon the shaft 23. This pawl is urged into engagement with the ratchet wheel by means of a spring and is disengaged through the medium of a hand lever 28, which is mounted for pivotal movement upon a standard 29, carried by the scoop. A rock shaft 30 is 95 mounted in a bearing carried by a cross bar 31 secured to the scoop and this rock shaft is provided at each end with a crank arm, one of said arms being connected to the pawl 26, by means of a rod 32, while the opposite 100 crank arm is connected to the lever 28, by means of a rod 33. By this means the lever 28 may be operated to release the dog from engagement with the ratchet wheel, whereupon the hinged plates 20 may be lowered 105 by gravity to open the scoop and deposit the load.

Secured upon the shaft 23 is an additional ratchet wheel 34, which is straddled by the bifurcated end of a hand lever 35. Mounted 110

within the bifurcated end of the lever 35 is a pawl 36, and this pawl is connected through the medium of a rod 37 to a pivoted hand grip carried by a lever 39. A spring 5 40 surrounding the rod 37 and positioned within a bracket 41 carried by the lever 35, acts to normally hold the pawl 36 from engagement with the ratchet wheel 34. When it is desired to raise the hinged plates 20 to 10 close the bottom of the scoop, the lever 35 is operated with the dog 36 in engagement with the ratchet wheel 34, which locks the lever to the shaft when the latter is moved in one direction and closes the bottom of the 15 scoop through the medium of the flexible connection 24.

The scoop 16 is mounted for vertical movement within the frame, and for this purpose there is provided upon each end of 20 the scoop a pair of substantially V-shaped guide rods 42. These rods operate in guides 43, carried by the frame.

Mounted in the frame 10 at the rear of the scoop 16, is a shaft 44, the latter being 25 mounted for free rotary movement within bearings carried by the frame. Loosely mounted upon the shaft 44, is a drum 45, the latter having wound thereon a chain or cable 46. This chain or cable passes over a 30 guide pulley 47, which is mounted upon a shaft 48, and is threaded through a pair of blocks 49 and 50. The first mentioned block is suitably supported above the scoop, while the block 50 is secured to the cross bar 31.

35 The drum 45 is held against rotation through the medium of a dog 51, the latter being operated by a hand lever 52, connected to the dog through the medium of rods 53 and a pivoted lever 54. This dog engages a ratchet wheel 55, secured to one face of the drum, while the opposite face of the drum has secured thereto a tapered clutch member 56. The member 56 is normally engaged by a brake band 57, which is 40 controlled by a tapered sleeve 58, mounted for sliding movement on the shaft 44. This sleeve engages an arm 59, which is pivotally secured to a disc 60, which disc is splined upon the shaft 44. The sleeve 58 has secured 45 thereto a lever 61, one end of which is pivotally secured to the cross bar 11, as indicated at 62, while its opposite end is pivotally secured to a foot lever 63, located within convenient reach of the operator. When it is 50 desired to release the drum, the dog 51 is disengaged from the ratchet wheel 55 by operating the lever 52. Pressure upon the lever 63 will then slide the sleeve 58 into engagement with the arm 59 and release the 55 drum 45, which will permit of a downward sliding movement of the scoop 16. The speed of this movement may be controlled by pressure upon the lever 63.

Secured to each of the traction wheels 13, 60 65 is a gear 64, the latter engaging idlers 65,

mounted upon short shafts 66, carried by the frame 10. The shaft 44 has each end extended through the frame 10, and has loosely mounted thereon a gear 67. The outer faces of the gears 67 are recessed, and mounted 70 within the recesses of each of these gears are pivoted dogs 68, the latter engaging ratchet teeth 69, formed upon the extremities of the shaft 44. If desired, the depressions in the gears 68 may be covered by a plate 70, so as 75 to exclude dust and dirt.

By this means a forward movement of the machine will rotate the shaft 44, which has normally locked thereon the drum 45, so that the scoop will be raised by power furnished by the forward movement of the machine. The ratchet connection of the gears 80 85 67 of the shaft 44 compensates for turning the machine, so that one wheel only will drive the shaft upon a turn.

It is believed that when the foregoing description is read in connection with the accompanying drawings, the construction, operation and advantages of the invention will 90 be apparent.

The invention is susceptible of various changes in its form, proportions and minor details of construction and the right is herein reserved to make such changes as properly fall within the scope of the appended 95 90 claims.

Having described the invention, what is claimed is:

1. A machine comprising a wheel supported frame, a scoop mounted for vertical movement therein, a shaft mounted for rotation in said frame, means connecting the wheels of the machine and said shaft for rotating the latter, a drum loosely mounted upon the shaft, a flexible element connecting the scoop and drum, whereby when the latter is rotated the scoop will be raised, means including a slidably mounted brake band carried by the shaft for normally locking the drum to the shaft and means for releasing 100 105 the brake band to lower the scoop.

2. A machine comprising a wheel supported frame, a scoop mounted for vertical movement therein, a shaft mounted for rotation in said frame, means connecting the wheels of the machine and said shaft for rotating the latter, a drum loosely mounted upon said shaft, a flexible element connecting the scoop and drum, whereby when the latter is rotated the scoop will be raised, means including a slidably mounted brake band carried by the shaft for normally locking the drum to the shaft and means including a tapered sleeve mounted for sliding movement upon the shaft for releasing the 110 115 120 125 brake band to lower the scoop.

3. A machine comprising a wheel supported frame, a scoop mounted for vertical movement therein, hoisting means operated by the wheels of the machine for raising the 130

- scoop and means including a brake controlled drum for controlling the downward movement of the scoop.
4. A machine comprising a wheel supported frame, a scoop mounted for vertical movement therein, a hoisting drum operated by the wheels of the machine for raising the scoop, a ratchet mechanism connected to one end of the drum, a brake band operating upon the opposite end of said drum and a laterally movable cam member for controlling the brake band.

5. A machine comprising a wheel supported frame, a scoop mounted for vertical movement therein and capable of being lowered to a filling position, a hinged bottom for the scoop, a shaft mounted for rotation upon the scoop and connected to the hinged bottom and a ratchet mechanism upon the shaft for controlling the position of the bottom. 15
